ELEVATED TANK

Filed Nov. 19, 1938

Inventor:
George T. Horton,
By Clinton Miles, Davis, Hirrell, & Dawson.
Attest:

UNITED STATES PATENT OFFICE

114,540

DESIGN FOR AN ELEVATED TANK

George T. Horton, Chicago, Ill.

Application November 19, 1938, Serial No. 81,229

Term of patent 14 years

To all whom it may concern:

Be it known that I, George T. Horton, a citizen of the United States, residing at Chicago, in the county of Cook and State of Illinois, have invented a new, original, and ornamental Design for an Elevated Tank, of which the following is a specification, reference being had to the accompanying drawing, forming a part thereof, in

which the figure is a perspective view of an elevated tank showing my new design.

I claim:

The ornamental design for an elevated tank, as shown.

GEORGE T. HORTON.
